UNITED STATES PATENT OFFICE.

HENRY GENSHIMER, OF CORONA, NEW YORK.

SEWING-MACHINE BINDER.

Application filed September 9, 1925. Serial No. 55,223.

This invention relates to binder attachments for sewing machines of the kind in which a strip of material is folded and fed in a direction at right angles to its initial direction of feed and in which the raw edges of the binding strip are folded over in readiness to be stitched to the material to be bound, whereby the necessity of first preparing the binding strip with its edges turned and 10 pressed down is avoided.

Binders of this character have heretofore been proposed in which a base plate is removably secured, with capacity for adjustment, to the bed plate of the machine and supports 15 the binder attachment which embodies a folding plate formed with an axial rib merging into a flat receiving space and having flanges formed with inwardly turned lips or wings to enclose a guide tongue cooperating with the 20 plate whereby the binding strip may receive a W-shaped cross-section. At the extreme delivery end of the plate the flanges have been formed with inwardly and rearwardly extending tongues which extend across the adjacent end edge of the guide tongue. Such 25 a folding plate as heretofore used has, of necessity, been formed of such relatively thick sheet metal, in order that it may hold its shape in use, that it has not been possible to give the 30 plate the requisite compound curvature to properly fold a binding strip with the greatest efficacy, especially if the strip is of a soft material; and wire and loops have also been provided on the delivery end of the flanges 35 to form inwardly projecting edges therefor which are not durable and involve a manual operation which has been found difficult, requires considerable time and generally results in an unsymmetrical formation, no two wires 40 being alike when affixed.

The present invention seeks to avoid the impractical features hereinbefore discussed by the provision of an outer shell member of 45 simple construction but of sufficient strength to adequately reinforce, when assembled therewith, a folding plate formed of sufficiently thin material that it can be given the requisite curvature. This shell member also 50 has formed thereon, by a die, in a stamping operation small fingers bent on the delivery end which, when the device is assembled, lie in spaced relation with the ends of the forming plate and guide tongue. The flanges are bevelled at the delivery end and recede from 55 the fingers with a gentle curvature to form what is in effect channels or guides from the

grooves in the folding plate to the notch therein from whence the folded material is directed at right angles to its previous direction of travel. With the construction just 60 described it is possible to adjust the tape backwardly in case of non-sewing.

Heretofore the base plate which supports the binder has been removably and adjustably secured to the bed plate of the machine 65 by screws or the like and by such construction the adjustment of the guide with respect to the needle has involved considerable skill, time and labor as well as necessitating the use of tools. The present invention seeks to provide a finer adjustment of the guide with respect to the needle by what may be termed a 70 micrometer adjustment wherein no tools are required. More particularly, the adjusting devices take the form of a pivoted lever operatively connected to the base plate eccentrically of the pivot whereby movement of the lever about its pivot will cause movement of the base plate to or away from the needle in a lesser degree, obviously, than the movement of the lever.

The invention also has to do with a convenient method of mounting the reel from which the tape is supplied to the binder in conjunction with the binder attachment whereby both 85 binder and reel may be handled as a unit. To this end the reel is carried upon the extremity of the adjusting lever or an extension thereof.

The invention further has for its object to provide a binder attachment which shall be 90 practical from the standpoint of convenience, ease and cheapness in manufacture and durability in use. To this end the component elements of the binder are formed of stampings which may be soldered together to form an 95 operative whole.

These and other objects of the invention and the means for their attainment will be more apparent from the following detailed description of a preferred embodiment there- 100 of which is illustrated in the accompanying drawings and in which:

Figure 1 is a view looking from above and showing the binder attachment supported upon the bed plate of a sewing machine and 105 the reel for supplying tape thereto;

Figure 2 is a front view, or a view looking from below in Figure 1, showing the binder attachment and supply reel therefor according to the present invention with a portion of 110 the guide strip broken away;

Figure 3 is a sectional view taken in the

plane indicated by the line 3—3 in Figure 2 and looking in the direction of the arrows and showing the various component elements going to make up the binder and a tape passing therethrough in process of being folded;

Figure 4 is a view in plan showing the outer shell member adapted to support the folding plate of the binder and to be in turn supported upon a bracket plate formed on the base 10 plate of the attachment;

Figure 5 is a view looking from the upper side in Figure 4 and showing the outer shell member of that figure;

Figure 6 is a view looking from above and 15 showing the folding plate according to the present invention;

Figure 7 is a view showing the folding plate, looking from above in Figure 6;

Figure 8 is a view showing the guide 20 tongue of the present invention;

Figure 9 is a view showing the guide tongue looking from above in Figure 8;

Figure 10 is a view in plan showing a clip which is adapted to secure the receiving end 25 of the guide tongue and the wings of the folding plate together; and

Figure 11 is a view looking from above in Figure 10 and showing the clip of that figure.

Referring to Figures 1 and 2 the bed plate 30 1, of a sewing machine is adapted to be secured thereto in any convenient manner as by screws passing through the apertures 2. The bed plate 1 is also provided with customary apertures 3 and 4 as will be understood and 35 an eye 5 for a needle. A presser foot is indicated in broken lines at 6. A base plate 7 having an upright bracket plate 8 along its front edge is ordinarily secured as by a screw or the like to the bed plate 1. In the 40 illustrated embodiment the bed plate is formed with a groove 9 adapted to receive a flange 10 formed on the rear or lower face of the base plate 7. The base plate 7 is also formed with an elongated aperture 11 having 45 a recess 12 at one side thereof. Immediately above the base plate there is disclosed a lever 13 pivotally mounted upon the bed plate 1 by a screw 14 passing through the elongated aperture 11 in the base plate and threaded 50 into a hole 15 in the bed plate of the machine. The lever also carries on its underside a lug 16 entering the recess 12. This lug is eccentric with respect to the pivot 14 whereby movement of the lever 13 about its pivot will 55 cause movement of the base plate 7 with respect to the groove 9 thereby moving the base plate nearer or further away from the needle eye 5.

Carried upon the projecting bracket plate 60 8 is the folding device or binder according to the present invention. The folder is formed of a plurality of component elements illustrated in Figure 4 through 11. Directly secured as by soldering or the like to the upper right bracket plate 8 is an outer shell member

indicated as a whole at 17 having a plain rear surface 18 turned slightly outwardly and rearwardly at the receiving end as at 19. At the delivery end the shell member is formed with a notch 20 and adjacent the delivery end 70 are carried flanges 21 rounding gently outward and provided respectively with inwardly directed tongues 22. The delivery end of the flanges are bevelled from the tongues 22 to the sides of the notch 20 and terminate in fingers 23 extending into the notch portion in substantially the plane of the rear surface 18.

The folding plate shown at Figures 6 and 7 is indicated as a whole at 24. It is formed 80 of very thin sheet metal by dies so that it may be given the proper gradations of curvature to permit it to fold even the softest of materials in a perfect manner. It is because of the light material of which it is formed that the 85 shell member is utilized to give adequate strength and rigidity to the folding plate after it is formed. The folding plate is formed at the receiving end with a substantially flat receiving face 25 having an outwardly and rearwardly deflected flange 26 which, when the folding plate is assembled upon the outer shell member is adapted to overlie and engage the end 19 of that member. The folding plate is formed with an axial rib 95 27 which merges into the receiving face 25 and is relatively high and narrow at the delivery end and deeply notched as at 28. Adjacent the receiving end the folding plate is formed with side flanges 29 terminating in 100 wings 30 which, adjacent the receiving end, are substantially parallel with the receiving face 25 but which converge with respect to the flange 29 as the axial rib increases in height. At the delivery end the folding plate is also formed with flanges 31 which rise sharply from the axial rib to form acute angle grooves or troughs 32. The flanges 31 after diverging for an appreciable distance from the axial rib to form in general a **W** 110 cross-section are turned inwardly and rearwardly as at 33, to serve as positioning means for a guide tongue 35 hereinafter to be described. Closing the notch formed by the rib 27 at the delivery end is a **U**-shaped flange 34 perpendicular to the plane of the paper as viewed in Fig. 6 and shown clearly in Figure 7 as extending beyond the rear marginal face of the folding plate. This flange is adapted 115 when the folding plate and outer shell member are in assembled relation to extend within the notch 20 of the shell member and with the flange 26 facilitate the positioning of the two elements.

The guide tongue 35 is illustrated in Figures 8 and 9 and is formed at the receiving end with a substantially flat face 36 and a start feed slot 37 midway between the ends. At the delivery end the tongue is notched as 120 at 38 to cooperate with the notch 28 of the 130

folding plate. The tongue is curved transversely to cooperate with the axial rib of the folding plate as will be understood. It is also formed with a bevelled receiving end shown 5 clearly in Figure 9 at 39 which receiving end is adapted to lie closely adjacent the wings 30 and to be held against said wings by means of the clip 40 illustrated in Figures 10 and 11. Since the tongue and folding plate are both 10 formed of very thin sheet metal in order that they may assume the requisite curvature, the clip 40 is availed of to secure the ends together and reinforce them with the aid of solder to produce a stiff construction at the 15 receiving end. This clip is U-shaped in cross-section as shown in Figure 11 at 41 and between the arms of the U-shaped portion are adapted to be received the ends 36 and wings 30. Side elements 42 are formed at the ends 20 of the U-shaped portion to overlie and reinforce the side flanges of the folding plate as will be understood from an inspection of Figures 1 and 2.

In the assembly of the device the folding 25 plate and guide tongue may be first assembled, the wings 30 and 33 serving to position the tongue with respect to the axial rib. The tongue may then be secured to the folding plate as by the clip 40 and solder may also be 30 availed of to further secure the two in operative position. The outer shell member and folding plate may then be assembled with the flange 26 overlying the edge 19 of the shell member and the flange 34 extending within 35 the notch 20, the tongues 22 overlying the wings 33 with the bevelled edges of the flanges 21 in spaced relation with respect to the delivery end of the folding plate. After the component elements of the device have 40 been suitably secured together the rear face of the outer shell member is secured to the front face of the upright bracket member carried with the base plate as clearly shown in Figures 1 and 2.

45 As the folding device or binder is directly carried upon the base plate and the base plate is capable of adjustment with respect to the needle eye 5 it follows that the binder is thus readily adjustable with respect to the needle eye without necessitating the use of a screw driver or other tool in the making of the adjustment.

50 Referring again to Figures 1 and 2 it will be observed that the lever 13 is formed with an extension 43 carrying a pin 44 at its extremity upon which is adapted to turn a reel 45 carrying the binding tape 46.

55 It will thus be seen that a binder attachment has been provided which is practical from the standpoint of manufacture and use. The construction provides for a guidance of the tape which facilitates its adjustment in a reverse direction in case of failure of the sewing device to properly secure the 60 tape to the material to be bound. Exact ad-

justment of the binder with respect to the needle is also possible with the device according to the present invention in a simple, convenient and expeditious manner, while the reel carrying the tape is so mounted as to be 70 a part of the attachment and capable of removal with the binding attachment as a unit.

75 It is to be understood that the various features hereinbefore enumerated are capable of independent use although mutually contributing to the desired end and no limitation is intended in the configuration and assembly according to the foregoing description and illustrations except as indicated in the accompanying claims.

80 Having thus described my invention I claim:—

1. In combination, a folding plate provided with a substantially flat receiving face, a notch formed at its delivery end, a rearwardly 85 extending flange formed on the back of the folding plate, an outer shell member substantially flat at its receiving end, a notch at the delivery end cooperating with the notch in the folding plate and receiving the flange on 90 the folding plate whereby the two are secured in operative position.

2. In combination, a folding plate provided with a substantially flat receiving face, a notch formed at its delivery end, a rearwardly 95 inclined edge formed on the plate at its receiving end, a rearwardly extending flange formed on the back of the folding plate, an outer shell member substantially flat at its receiving end, and provided with a rearwardly 100 inclined edge to cooperate with the edge on the plate, a notch at the delivery end cooperating with the notch in the folding plate and receiving the flange on the folding plate, the notch and receiving means securing the two 105 in operative position at the delivery end and the cooperating edges securing them at the receiving end.

3. In combination, a folding plate provided with a substantially flat receiving face, a 110 notch formed at its delivery end, the edges of the notch being formed as a rearwardly extending flange on the back of the folding plate, an outer shell member substantially flat at its receiving end, a notch at the delivery 115 end cooperating with the notch in the folding plate, the notch in the outer shell being sufficiently over-sized to receive the flange on the folding plate, whereby the two are secured in operative position.

4. In combination, a folding plate, a notch formed therein at its delivery end, a rearwardly 120 extending flange formed about the notch, an outer shell member, forwardly extending flanges formed thereon adjacent its delivery 125 end and tapering down to the delivery end, a notch in the outer shell at its delivery end to receive the rearwardly extending flange on the folding plate and cooperate with the first notch, and fingers formed at the delivery end 130

of the outer shell and extending into the notch, the taper of the flanges terminating in the fingers.

5. In combination, a folding plate, a notch formed therein at its delivery end, a rearwardly extending flange formed about the notch, an outer shell member, forwardly extending flanges formed thereon adjacent its delivery end and tapering down to the delivery end, a notch in the outer shell at its delivery end to receive the rearwardly extending flange on

the folding plate and cooperate with the first notch, and fingers formed at the delivery end of the outer shell and lying in the plane thereof, said fingers extending toward one another ¹⁵ into the notch, the taper of the flanges terminating in the fingers.

Signed at New York, in the county of New York and State of New York this 8th day of September A. D. 1925.

HENRY GENSHEIMER.
